UNITED STATES PATENT OFFICE.

LOTHAR R. ZIFFERER, OF NEW YORK, N. Y.

EXPANSION-BOLT.

1,121,963.

Specification of Letters Patent.

Patented Dec. 22, 1914.

Application filed December 12, 1913. Serial No. 806,270.

To all whom it may concern:

Be it known that I, LOTHAR R. ZIFFERER, a citizen of the United States, residing at New York, in the county and State of New York, have invented certain new and useful Improvements in Expansion-Bolts, of which the following is a specification.

This invention relates to expansion bolts, such as are commonly anchored within bodies of solid material, like concrete or masonry, being particularly concerned with the construction of an expansion bolt shield and with a cap-piece designed for attachment thereto.

15 In this invention, I have aimed to provide between an expansion shield and cap-piece an interlocking connection which permits of sufficient play or swinging movement to enable the cap-piece to adjust itself squarely 20 against the face of the material within which the expansion bolt is anchored, regardless of whether or not the hole for the shield be drilled exactly perpendicular to the surface of the wall. It is also sought 25 to provide a connection between the cap-piece and expansion shield which is independent of the bolt or lag-screw which may be used to produce the expanding action.

As a further object, I have provided that 30 this interlocking connection should be non-rotatable, whereby the expansion shield may be rotated or screwed into position, and its movement be predetermined through the agency of the cap-piece.

35 The invention further consists in numerous other features of construction and combination of parts which are hereinafter described and claimed.

It is well known that in many instances 40 the holes drilled to receive expansion bolts should be concealed, both to present a better appearance, and to prevent the escape of pulverized material which may remain or accumulate within such holes, and which, 45 through vibrations or other causes, frequently tends to fall therefrom. To this end, I have provided a cap-piece preferably of ornamental configuration and suitable finish, which is an independent entity 50 in itself. Cap pieces designed for such purposes are commonly defective in that they become dislocated sooner or later, so that

they no longer perform their intended function. In my invention, however, the interlocking connection between the cap-piece 55 and the shield is made permanent and secure, so that movement or displacement of the cap-piece from its original position cannot take place. In the present invention, moreover, the cap-piece and expansion 60 shield are so constructed that this interlocking connection becomes permanent through the insertion of a bolt or lag-screw which is used to expand the shield. Furthermore, the depth to which the expansion shield may 65 sink within the hole for its reception is in the present invention automatically predetermined through the agency of the cap-piece, which acts as a stop to limit the position of the expansion bolt. It has not been 70 uncommon to provide the exterior of expansion shields with spiral threads to facilitate insertion of the device within a snug hole and particularly where the surrounding material is comparatively soft, 75 but without the provision of some means at the outer end of the expansion shield, by which this threading action is continued to completion, the function of the spiral threads cannot be effectively performed. 80 The interlocking and non-rotatable connection between the cap-piece and the shield, which I have provided, enables the cap-piece to be used as a means by which the expansion shield may be rotated and advanced 85 into such a hole.

In the drawing:—Figure 1 is a cross section taken through a body of solid material, such as concrete, showing in elevation the present expansion bolt anchored therein, and 90 the cap-piece secured thereto on the face of the wall, the interlocking connection therebetween being shown in cross section; Fig. 2 is an elevation of the cap-piece looking directly toward the face of the wall; Fig. 3 is 95 a view similar to Fig. 2, showing the cap-piece modified slightly to provide a wrench hold; Fig. 4 is a view of the rear or bearing side of the cap-piece; Fig. 5 is a cross section through Fig. 1 taken on line 5—5, looking in the direction of the arrows; and Fig. 6 is a view similar to Fig. 5, showing a slightly modified form of expansion shield 100 and cap-piece.

In the drawing, Fig. 1, there is shown a section of a body of material 7, within which is anchored an expansion bolt, the shield 8 of which is represented as formed 5 with spiral threads 9 upon its exterior arranged to engage with the sides of the hole drilled to receive the device. Near its outer end, the expansion bolt is provided with a neck 10 of reduced size relatively of the 10 body of the shield, and at its extreme outer end a flange 11 is formed, constituting, in effect, a head. The operation of expansion is produced in the ordinary way as through the agency of a nut 12 adapted to be advanced against inclined surfaces through rotation of a threaded bolt or lag screw 13, or, 15 if preferred, through the agency of a lag-screw engaging with inclined faces on the interior of the expansion shield. Both of 20 these types of expansion bolt are well recognized, and further description is here deemed unnecessary.

Upon the face of the wall within which the expansion bolt is secured is a cap-piece 25 14, here represented as circular in formation, having a central opening 15 through which the bolt 13, (or lag-screw if used) may pass. As best shown in Fig. 2, the inner or bearing side of the cap-piece is 30 formed to provide an undercut recess 16 extending laterally and radially within the body thereof, and having at one end an enlarged entering portion 17; the undercut recess is formed with a cross section substantially T-shaped, as best shown in Fig. 35 1. The cap-piece may be caused to engage with the expansion bolt shield by bringing the enlarged portion 17 of the recess 16 over the flanged head 11, and thereafter moving 40 the cap-piece laterally until, in final position, the expansion shield is centered within the cap-piece, enabling the bolt 13, (or lag-screw is used) to be introduced into the shield through the opening 15 which is arranged to align with the axis of the expansion bolt. An inspection of the figures in 45 the drawing will show that the length of the recess 16 is such that the axes of the expansion shield and cap-piece will align 50 when the attaching movement above described has been substantially completed. The interlocking connection thus established is made permanent by inserting the bolt, (or lag-screw if used) through the opening 55 15 into the expansion bolt shield. The inner wall of this recess against which the head of the shield abuts is rounded at the entering portion not only to remove any obstruction to the lateral movement of the shield 60 in either direction, but to assist in guiding the head of the shield to a position of disengagement when it is desired to remove one part from the other.

In actual practice, the cap-piece would 65 probably be made of cast metal with the re-

cess 16 of sufficient size to permit the head 11 of the expansion shield to engage somewhat loosely therein, so that a limited amount of play or swinging movement could take place to enable the cap-piece to adjust 70 itself squarely against the face of the wall where it is to be used. This in no way prevents a tight impingement of the cap-piece against the wall when a bolt or lag-screw is screwed home, and a fixture attached in 75 place. Furthermore, as will be hereinafter explained, the cap-piece locks non-rotatably with the expansion shield, so that the cap-piece may be revolved, and produce a corresponding rotation of the expansion shield 80 prior to expansion within the hole, which, if of proper size and constituency, will allow the threads on the expansion shield to take hold, thus causing an inward movement thereof, and causing the cap-piece to be 85 tightly impinged against the wall. In Fig. 3, the cap-piece is shown slightly modified to provide a wrench hold, enabling an appropriate tool to be used to effect this rotation under circumstances where a hand hold 90 would not suffice.

The neck portion of the expansion bolt is shown in cross-section in Fig. 5, as lying substantially in the plane of the narrower portion of the recess 16. The expansion bolt in this figure consists of two shells held together by tongues or lugs 18 formed on one shell which overlie or embrace the other shell, these tongues being located in the plane of the neck portion, and producing 95 an enlargement therein in one direction through the axis of the shield. When so arranged, the cap-piece can be attached to the expansion shield with the recess 16 parallel 100 only to the larger diameter of the neck of the shield. Any tendency of the cap-piece to revolve upon the expansion bolt shield causes the said lugs or tongues to engage with the sides of the recess 16, and thereby 105 prevent anything more than a very limited rotary movement in either direction. For this reason, it is possible to rotate the cap-piece and produce a corresponding rotation 110 on the part of the expansion shield. It is not at all essential to the present invention, however, that the expansion bolt shield consists of two or more shells, since obviously a one-piece shield, having a member on its outer end answering to the head 11 to engage within the recess of the cap-piece, will 115 operate to produce an interlocking connection in precisely the same way. Where the part engaging within any of the portions of the recess 16 is so configured as to present 120 any obstruction against the turning of the expansion bolt shield within said recess, as, for instance, by elongating the neck as in Fig. 5, or by providing a lug or other protruding member, the same non-rotating effect 125 will result. In Fig. 6, a modification is 130

shown of the construction above suggested. In this case, a plurality of projecting members are arranged in the plane of the neck of the expansion shield to engage with appropriate portions of the recess 16 to prevent rotation therein.

5 The head of an expansion bolt shield in many instances is commonly formed with an annular flange which, for the purposes 10 of this invention, is admirably suited to engage with the cap piece. This construction, however, may be modified without departing from the spirit of the present invention, as, for instance, when one or more projections are utilized which constitute members 15 capable of lying within the undercut recess 16. It is manifest that little regard for the appearance of the outer end of the expansion shield need be had, since the expansion 20 bolt is effectually concealed from view when the cap-piece is placed with its bearing side against the body of the material within which the device is anchored. Since the cap-piece is used chiefly for the purpose of 25 preventing material from falling out of the hole, and for presenting a finished and attractive appearance, it follows that the cap-piece will ordinarily be polished or machined, thus rendering it quite different in 30 finish from the expansion bolt shield. For this reason, its construction, as a distinct entity from the expansion bolt, is highly desirable.

It is apparent, of course, that the cap-piece 35 may be withdrawn from the expansion bolt shield by a reversal of the movements which have been described. When the bolt or lag-screw used to produce expansion is entered into the shield and screwed home, the attachment of the cap piece to the shield 40 becomes permanent, and no chance of its slipping or dropping away from the shield, or rotating thereon can ever occur, but, if even the expansion bolt is no longer to be 45 used, the cap-piece may be removed without detriment, by withdrawing the bolt (or lag-screw if used) and thereafter disengaging the cap-piece from the head of the shield.

As long as the cap-piece remains connected 50 operatively with an expansion shield consisting of two or more shell segments, the expanding action will be confined entirely to the inner end of the shield where there is the least likelihood of crumbling or 55 cracking of the material against which the expansion is exerted, due to the unyielding engagement of the sides of the recess 16 with the neck of the shield. The lugs or tongues used to effect a connection between 60 the shell segments serve to maintain the device in an assembled condition, but unless a positive means, such as the cap-piece described, is used at the time of expansion to prevent releasing or unlocking of such a 65 temporary binder, the shield is apt to be ex-

panded throughout its entire length with results detrimental to the surrounding material.

I claim:

1. The combination with an expandible 70 shield composed of two segmental shells formed with a flange on the outer end thereof, each said shell having a neck portion of reduced size adjacent said flange, and one of said shells having a tongue arranged to engage with the other in said neck portion, of a cap-piece arranged to engage with said shield, and to lock permanently therewith when said shield is expanded, said tongue being arranged to engage with said 75 cap-piece to prevent rotary movement thereof with respect to said shield, substantially as described.

2. The combination with an expandible 80 shield, having an out-turned flange on its outer end, and having its expansion produced through the actuation of a member entering the shield from the outer end thereof, of a cap-piece formed with an axial bore extending through the body thereof, and 85 with a recess enlarged at one end and T-shaped in cross section extending laterally within the body of said cap-piece and terminating substantially in line with said bore, and adapted to receive the flanged end 90 of said shield therein when entered through the said enlarged end of the recess, and to be permanently locked therein when an actuating member is introduced into said shield 95 for expanding the same, substantially as described.

3. The combination with an expandible 100 shield, having an out-turned flange on its outer end, and a neck adjacent thereto having unequal diameters, of a cap-piece provided on its bearing side with a T-shaped recess, said flanged end of the shield lying within the head of the recess and the neck portion within the body of the recess, with its shorter diameter pointed transversely 105 thereof, whereby the longer diameter of said neck serves to prevent rotation between said cap-piece and shield, substantially as described.

4. The combination with an expandible 110 shield having spiral grooves arranged on the exterior thereof and capable of being expanded at the inner end thereof, of a member adapted to engage unyieldingly and non-rotatably with the outer end of said shield to prevent expanding action at such point, said member serving as a medium for rotating said shield within a hole, substantially as described.

5. The combination with an anchoring 115 device having a projecting member on its outer end, of a cap piece provided with an undercut recess in the body thereof, said recess constituting with the said member an interlocking connection capable of being 120 125

dis-established prior to expansion by a relative lateral movement, substantially as described.

6. The combination with an expandible shield having an outturned flange on its outer end, of a cap piece arranged when moved in a lateral direction only to engage with the flanged end of said shield, and to lock permanently therewith when said shield is expanded, substantially as described.

7. The combination with an anchoring device having an outturned flange on its outer end, of a cap piece arranged when moved in a lateral direction only to be engaged non-rotatably with said device, and means for thereafter preventing a return lateral movement of the said cap piece with respect to said device, whereby a permanent interlocking connection is established, substantially as described.

8. The combination with an anchoring device having a flange arranged on its outer end, of a cap piece provided on its bearing side with an undercut recess, said recess constituting with the said flange an interlocking non-rotatable connection capable of being dis-established prior to expansion by a relative lateral movement, substantially as described.

9. The combination with an expandible shield having an outturned flange and a neck of reduced size near its outer end, and having its expansion produced through the actuation of a member entering the shield from its outer end, of a cap piece arranged when moved in a lateral direction only to be guided into engagement with the flange and neck portion of said shield, and to be permanently interlocked therewith when said actuating member is introduced into the shield, substantially as described.

10. The combination with an expandible shield having an outturned flange and a neck of reduced size near its outer end, and having its expansion produced through the actuation of a member entering the shield from its outer end, of a cap piece arranged when moved in a lateral direction only to be guided into a non-rotatable engagement with the said flange and neck portion of said shield, and to be permanently interlocked therewith when said actuating member is introduced into the shield, substantially as described.

11. The combination with an expandible shield having one or more projecting members adjacent its outer end, of a cap piece arranged when moved in a lateral direction only to be guided into engagement with said shield and to be permanently locked therewith when said shield is expanded, said projecting members serving to prevent rotation of said cap piece with respect to said shield, substantially as described.

12. The combination with an expandible shield having an outturned flange on its outer end, and having its expansion produced through the actuation of a member entering the shield from the outer end thereof, of a cap piece formed with an undercut recess enlarged to provide an entering portion at one end, and adapted to receive the flanged end of said shield therein when entered by a lateral movement in one direction through the said entering portion, and to be permanently locked therein when an actuating member is introduced into the shield for expanding the same, substantially as described.

13. The combination with an expandible shield having an outturned flange on its outer end and having its expansion produced through the actuation of a member entering the shield from the outer end thereof, of a cap piece formed with a laterally extending undercut recess in the body thereof enlarged at one end to provide an entering portion, and adapted to receive the flanged end of said shield therein when entered by a lateral movement through said enlarged portion of the recess, and to be permanently locked therein when an actuating member is introduced into the shield for expanding the same, and means for preventing rotation of said cap piece with respect to said shield.

14. The combination with an anchoring device having an outturned flange on its outer end, of a cap piece arranged when moved laterally in one direction to engage with the flanged end of the device, said cap piece being capable of a limited swinging movement when so interlocked, substantially as described.

15. The combination with an expandible shield having an outturned flange on its outer end, of a cap piece arranged when moved laterally in one direction to engage with the flanged end of the shield, and to lock permanently therewith when said shield is expanded, said cap piece being capable of a limited swinging movement when so interlocked, substantially as described.

16. The combination with an expandible shield having an outturned flange on its outer end, of a cap piece arranged when moved laterally in one direction to engage non-rotatably with the flanged end of said shield, and to lock permanently therewith when said shield is expanded, said cap piece being capable of a limited swinging movement when so interlocked, substantially as described.

17. The combination with an expandible shield having an outturned flange and a neck adjacent thereto having unequal diameters, said shield being capable of expansion through the actuation of a member entering the shield from its outer end, of a cap

- piece arranged when moved laterally in one direction to engage with the said flange and neck portion of said shield, certain of said engaging portions coöperating to prevent 5 rotation of the shield with respect to the cap piece, said shield and cap piece being permanently interlocked when an actuating member is introduced into the shield, substantially as described.
- 10 18. The combination with an anchoring device having spiral grooves arranged on the exterior thereof, of a cap piece attachable to said device to form a non-rotatable connection therewith, whereby said cap piece 15 serves as a medium for rotating said shield within a hole, said cap piece being attachable and detachable when moved only in a lateral direction, substantially as described.
19. The combination with an expansible 20 shield having spiral grooves arranged on the exterior thereof, of a cap piece attachable to said expansible shield through a lateral movement to form a non-rotatable connection therewith, whereby said cap piece 25 serves as a medium for rotating said shield within a hole, said cap piece being capable of a limited swinging movement with respect to said shield, and means for locking said cap piece against return lateral movement, said means serving also to cause said shield to expand within the hole, substantially as described.
20. The combination with an expansible 30 shield capable of being expanded at its inner end, of a member adapted when moved laterally in one direction to engage unyieldingly with the outer end of said shield to prevent expanding action at such point, said member being prevented from moving laterally in the opposite direction to unlock from said shield when expansion is commenced, substantially as described.
21. The combination with an expansible 35 shield consisting of a plurality of shells releasably bound together, and capable of being expanded at its inner end, of a member adapted when moved laterally in one direction to engage unyieldingly with the outer end of said shield to prevent expanding action at such point, said member being capable of a limited free swinging movement with respect to the shield and about the axis thereof, substantially as described.
22. The combination with an anchoring 40 device having an outturned flange on its outer end, of a cap piece arranged when moved laterally in one direction to engage with the flanged end of the device, and when moved laterally in the opposite direction to be disengaged from the device, substantially as described.
23. As a new article of manufacture, a 45 cap piece of symmetrical configuration having in the body thereof an undercut recess disposed adjacent one of its faces, the said recess terminating in an entering portion opening onto said face, substantially as described.
24. As a new article of manufacture, a 50 cap piece having a bore extending therethrough and an undercut recess in the body of the cap piece arranged to intersect said bore, substantially as described.
25. As a new article of manufacture, a 55 cap piece having a bore extending therethrough, and an undercut recess in the body of the cap piece arranged to intersect said bore, the said recess terminating in an entering portion adjacent one of the faces of the cap piece, substantially as described.
26. As a new article of manufacture, a 60 cap piece having a portion of its exterior configured to provide a bearing surface, and an undercut recess in the body of the cap piece adjacent said bearing surface, one 65 end of said recess being enlarged to provide an entering portion facing on said bearing surface, substantially as described.
27. As a new article of manufacture, a 70 cap piece having a portion of its exterior configured to provide a bearing surface, and an undercut recess in the body of the cap piece adjacent said bearing surface, one 75 end of said recess being enlarged to provide an entering portion facing on said bearing surface, said cap piece being provided with a bore extending into the body thereof and arranged to intersect said recess, substantially as described.
28. As a new article of manufacture, a 80 cap piece provided with a bore extending therethrough, and a recess extending laterally from said bore within the body of the cap piece, the said recess terminating adjacent one of the faces of the cap piece in an 85 entering portion, the walls whereof are rounded to facilitate passage therethrough, substantially as described.
29. As a new article of manufacture, a 90 cap piece embodying a bearing face, the 95 walls adjacent said face being obliquely inclined at a substantially acute angle, an opening into the body of the cap piece on the bearing face adjacent one of the inclined walls, the inner wall of said opening having an inclination corresponding somewhat to that of the said exterior wall, and an undercut recess communicating with said opening extending adjacent said bearing face within the body of the cap piece, substantially as described.
30. As a new article of manufacture, a 100 cap piece embodying a bearing face, the 105 walls adjacent said face being obliquely inclined at a substantially acute angle, an opening into the body of the cap piece on the bearing face adjacent one of the inclined walls, the inner wall of said opening having an inclination corresponding somewhat to that of the said exterior wall, and an 110 undercut recess communicating with said opening extending adjacent said bearing face within the body of the cap piece, substantially as described.
31. As a new article of manufacture, a 115 cap piece embodying a bearing face, the 120 walls adjacent said face being obliquely inclined at a substantially acute angle, an opening into the body of the cap piece on the bearing face adjacent one of the inclined walls, the inner wall of said opening having an inclination corresponding somewhat to that of the said exterior wall, and an 125 undercut recess communicating with said opening extending adjacent said bearing face within the body of the cap piece, substantially as described.

dercut recess communicating with said opening extending adjacent said bearing face within the body of the cap piece, the end of said recess opposite the said opening being intersected by a bore extending through the body of the cap piece, substantially as described.

31. As a new article of manufacture, a cap piece having in the body thereof an

undercut recess disposed adjacent one of its faces, the said recess terminating in an enlarged entering portion opening onto said face, substantially as described.
